[57] **CLAIM**

The ornamental design for a combined bed and headboard with extensible armrests therefor, as shown and described.

DESCRIPTION

FIG. 1 is a left side elevational view of a combined bed and headboard with extensible armrests therefor showing my new design, the right side being a mirror image thereof;

FIG. 2 is a top front perspective view thereof;

FIG. 3 is a top front perspective view thereof, with the armrest members in a retracted position; and

FIG. 4 is a top plan view of that shown in FIG. 1.

FIG. 1

FIG. 2

FIG. 3

FIG. 4
